W. C. LOONEY

SPACE BAND

Filed March 8 1927

UNITED STATES PATENT OFFICE.

WALTER C. LOONEY, OF DANVILLE, KENTUCKY.

SPACE BAND.

Application filed March 8, 1927. Serial No. 173,776.

My invention relates to improvements in space bands or devices adapted to be placed between the words in linotype compositions.

My improved construction is especially adapted for use in connection with lines of matrices, each line carrying characters employed in casting. My spacing device may be employed and operated in a similar manner to the ordinary space bands used in the 10 Mergenthaler and other types of line casting machines.

The operators of type setting machines have to hand space about every third or fourth line being set. This hand spacing is 15 tedious and causes much loss of time in the operation of the machine.

My space band is automatic in operation, and is adapted to provide a space as thin as the regular news matter space band, when 20 only a thin space is needed, and will also provide a much thicker space, when needed. My space band is further so constructed that its adjustable parts will automatically return to the lowermost positions when or before 25 these bands are being returned to the space band box. My space band is, therefore, automatic and will eliminate hand spacing.

In the accompanying drawings, forming a part of this specification, and in which like 30 numerals are employed to designate like parts throughout the same,

Figure 1 is a front elevation of a space band embodying my invention,

Figure 2 is an elevation of the rear side 35 thereof,

Figure 3 is an edge elevation of the space band,

Figure 4 is an elevation of the opposite edge, which is next to the mold, when the 40 line is cast,

Figure 5 is an edge elevation of the device, showing the upper wedge shaped spacing member elevated,

Figure 6 is a similar view showing both 45 the upper and lower wedge shaped spacing members elevated,

Figure 7 is a transverse section taken on line 7—7 of Figure 1,

Figure 8 is a similar view taken on line 50 8—8 of Figure 1,

Figure 9 is a side elevation of the lower end of the wedge shaped space band member, showing the tongue or carriage secured thereto,

Figure 10 is a longitudinal section taken 55 on line 10—10 of Figure 1, and,

Figure 11 is a fragmentary side elevation of the opposite side of the upper spacing member from the side shown in Figure 9.

In the drawings, wherein for the purpose 60 of illustration, is shown a preferred embodiment of my invention, the numeral 5 designates a relatively stationary wedge shaped space band member, constituting the body portion of the device. This space band member remains stationary in the line of matrices. The space band member 5 increases in thickness upwardly, as shown. Disposed upon one side of the space band member 5 and rigidly attached thereto is a guide tongue 6. 70 This guide tongue projects laterally beyond the space band member 5 and has its edges beveled or undercut, as indicated at 7. The tongue 6 projects a slight distance below the bottom end of the space band member 5. 75 The space band member 5 has a portion of its material, at one longitudinal edge, cut away, affording a shoulder 8.

The numeral 9 designates an intermediate wedge shaped spacing member, increasing in 80 thickness downwardly, and having its inclined face slidably engaging the inclined face of the space band member 5, the outer faces of these members remaining parallel. The spacing member 9 is provided with a 85 longitudinal slot 10, having beveled side walls 11, and this slot receives the tongue 6, which is slidable therein, but can not move laterally out of the same. The slot 10 is continued at its lower end through a tongue 12,

arranged upon one side of the spacing member 9, rigidly secured thereto, and projecting laterally therebeyond. This tongue has 90 its longitudinal edges beveled or undercut, as shown at 13. The tongue 12 projects beyond the lower end of the spacing member 9, as shown. This spacing member 9 is provided near its lower end with a laterally projecting stop pin 14, adapted to engage the shoulder 8, thereby limiting the upward movement of 100 the spacing member 9, with relation to the space band member 5 and retaining the parts

permanently connected. At its lower end, and adjacent to the edge thereof which is next to the mold when the line is cast, the 105 wedge shaped spacing member is provided with a longitudinal rib 15, which follows the reversely inclined or beveled face 16, at

the lower end of the spacing member 9. The upper end of the spacing member 9 is curved and blunt, and not sharp so that it will not catch on the matrices, when the slide is 5 working.

The numeral 18 designates a lower wedge shaped spacing member increasing in thickness downwardly and having its inclined face slidably engaging the inclined or beveled face 16 while its outer face remains parallel with the outer face of the space band member 15. This lower spacing member 18 is provided with a longitudinal groove 19, the side walls of which are inclined or undercut, and the tongue 12 slides 10 within this groove, but can not be laterally displaced therein. The spacing member 18 is provided near one edge with an auxiliary longitudinal groove 20, for receiving the 15 longitudinal rib 15, this rib and groove connection forming a tight joint, located adjacent to that edge of the device which is next to the mold, when the line is cast, thereby preventing squirting of the molten metal.

20 The lower wedge shaped spacing member 18 is provided in the groove 20 with a stop element 21 adapted to engage the lower end of the longitudinal rib 15 thereby limiting the upward movement of the spacing member 18 with respect to the spacing member 9 and retaining the parts permanently connected. Particular attention is called to the fact that the spacing member 18 is tapered 25 throughout substantially its entire length.

30 The spacing member 18 is provided in its side wall with a longitudinal opening 21' for receiving a trigger 22, pivoted to the spacing member at the lower end of the trigger as shown at 23. A spring 24 is provided, which serves to swing the upper end 35 of the trigger laterally so that it enters the groove 19, in the path of travel of the tongue 12, thus locking the member 18 against upward movement with relation to the member 9. One corner of the upper end 40 of the trigger 22 is rounded, at 25, and this rounded edge is adapted to be engaged by the tongue 6, when the spacing member 9 approaches the uppermost position with respect to the space band member 5, and since 45 the tongue 6 is in a plane in advance of the bottom wall of the longitudinal groove 10, this tongue 6 will shift the trigger 22 laterally, whereby it will disengage the lower 50 end of the tongue 12, and the member 18 will be free to move upwardly with respect to the member 9 so that both members may assume the raised position, indicated in Figure 6. The outward movement of the trigger 22, due to the action of the spring 24, is limited by lugs 26 adapted to engage within recesses 27.

The casting area of the device is indicated as between the lines *a*, *a*, Figure 5.

55 In operation, the wedge shaped space

band member 5 is relatively stationary, and co-operates with the wedge shaped spacing member 9, whereby their outer faces are parallel, their reduced ends extending in opposite directions. When the desired spacing function can be obtained by the adjustment of the member 9 alone, the member 18 remains locked to the member 9, and moves upwardly with the member 9. When a greater spacing function is required, the 70 continued upward movement of the member 9 will bring the tongue 6 into engagement with the trigger 22, shifting this trigger inwardly so that it will disengage the tongue 12, and the member 18 will now travel upwardly with respect to the elevated member 9, the two members assuming the position shown in Figure 6, whereby the maximum spacing function is obtainable. It is thus seen that two wedge shaped spacing members are employed, the lower spacing member remaining locked to the upper spacing member until the upper spacing member has been raised to or near its upper maximum spacing position. The locking engagement 75 between the two spacing members is then automatically broken and the lower spacing member may then slide upwardly upon the intermediate spacing member.

80 The action of the type setting machine in returning the spacing bands to the space band box causes my device to resume its original position with both spacing members in the lowermost position before it arrives at the box, but if for any reason this 85 action should not occur, by the time the same reaches the space band box, it will take place, when the device drops into the assembler, as the operator is composing the line, which makes it doubly sure of being 90 in the proper adjustment by the time the device returns to the casting mechanism.

95 It is to be understood that the form of my invention, herewith shown and described, is to be taken as a preferred example of the same, and that various changes in the shape, size and arrangement of parts may be resorted to without departing from the spirit of my invention, or the scope of 100 the subjoined claims.

105 Having thus described my invention, I claim:-

110 1. A space band comprising a wedge shaped relatively stationary space band member provided with a laterally projecting tongue extending below the bottom end of the space band member, a wedge shaped spacing member having a longitudinal groove for the reception of the tongue and provided at its lower end with a tongue 115 through which the groove extends, the tongue carried by the space band member being adapted to project laterally beyond the bottom wall of the groove in the tongue carried by the spacing member when said space 120 member is relatively stationary.

ing member is moved upwardly to approach the end of its travel, a second wedge shaped spacing member having a longitudinal groove receiving the tongue carried by the 5 first named spacing member, and a spring-pressed trigger carried by the second named spacing member and adapted to project into the path of travel of the tongue carried by the first named spacing member for locking 10 the second named spacing member against upward movement with relation to the first named spacing member, said trigger being adapted to be directly engaged by the tongue carried by the space band member and to 15 be shifted laterally thereof.

2. A space band comprising a wedge shaped relatively stationary space band member provided with a laterally projecting tongue, a wedge shaped spacing member provided at its lower end with a laterally projecting tongue and having a longitudinal groove extending through its tongue, the tongue carried by the space band member operating within the groove of the spacing 25 member and adapted to assume a position at one side of and in contact with the tongue of said spacing member, a second wedge shaped spacing member having a longitudinal groove to receive the tongue of the first 30 named spacing member, and a spring pressed trigger pivoted upon the second named spacing member and projecting laterally into the path of travel of the tongue of the first 35 named spacing member and the tongue of the space band member, said trigger having an inclined part to be directly engaged by the tongue of the space band member.

3. A space band comprising a wedge shaped relatively stationary space band member provided with a laterally projecting tongue, a wedge shaped spacing member pro-

vided near its lower end with a laterally projecting tongue and having a longitudinal groove extending through its tongue, the tongue carried by the space band member 45 operating within said groove and adapted to assume a position at one side of the tongue of said spacing member, a second wedge shaped spacing member having a longitudinal groove to receive the tongue of the first 50 named spacing member and having its upper end rounded and blunt, and a spring pressed trigger pivoted upon the second named spacing member and projecting laterally into the path of travel of the tongue of the first 55 named spacing member and the tongue of the space band member, said trigger having an inclined part to be directly engaged by the tongue of the space band member.

4. A space band comprising a wedge 60 shaped relatively stationary space band member provided with a laterally projecting tongue, a wedge shaped spacing member provided near its lower end with a laterally extending tongue and having a longitudinal 65 groove extending through its tongue, a second wedge shaped spacing member having a longitudinal groove receiving the tongue of the first named spacing member, a pivoted trigger carried by the second named spacing 70 member and adapted to directly engage the tongue of the first named spacing member and also adapted to be directly engaged by the tongue of said space band to be shifted laterally thereby, and means arranged adjacent to one longitudinal edge of the space 75 band for effecting a tongue and groove joint between the first and second named spacing member.

In testimony whereof I affix my signature.

WALTER C. LOONEY.
